US0D1000410S

(12) **United States Design Patent** (10) **Patent No.:** **US D1,000,410 S**
(45) **Date of Patent:** **** Oct. 3, 2023**

(54) **AUDIO HEADSET**

(71) Applicant: **YI ZHAO (SHENZHEN) CO., LIMITED**, Shenzhen (CN)

(72) Inventor: **Mingxun Zheng**, Yanji (CN)

(**) Term: **15 Years**

(21) Appl. No.: **29/812,360**

(22) Filed: **Oct. 20, 2021**

(51) LOC (14) Cl. **14-01**

(52) U.S. Cl.

USPC **D14/205**; D14/206

(58) **Field of Classification Search**

USPC D14/205, 206, 188, 192; D29/112; 2/209; 381/380-381, 374; 428/30

CPC H04R 25/00; H04R 25/02; H04R 1/1066;

H04R 1/1016; H04R 5/033; H04R 5/0335; H04R 1/1058; H04R 1/105

See application file for complete search history.

Howard M. Cohn

(57) **CLAIM**

The ornamental design for an audio headset, as shown and described.

DESCRIPTION

FIG. 1 is a perspective view of an audio headset showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 2; and,

FIG. 11 is an enlarged view of portion 11 shown in FIG. 3. The dot dash dot broken lines encircling portions of the audio headset in FIG. 1 and illustrated in the enlarged view of FIG. 9, FIG. 2 and illustrated in the enlarged view of FIG. 10, and, FIG. 3 and illustrated in the enlarged view of FIG. 11 form no part of the claimed design.

1 Claim, 11 Drawing Sheets
